139,181

DESIGN FOR A LAWN SWING OR SIMILAR ARTICLE

Charles L. Mock, Newark, Ohio

Application June 3, 1944, Serial No. 113,852

Term of patent 3½ years

(Cl. D15—11)

To all whom it may concern:

Be it known that I, Charles L. Mock, a citizen of the United States, residing at Newark, in the county of Licking and State of Ohio, have invented a new, original, and ornamental Design for a Lawn Swing or Similar Article, of which the following is a specification, reference being had to the accompanying drawings, forming a part thereof.

Fig. 1 is a perspective view of a lawn swing or similar article showing my new design;

Fig. 2 is a top plan view of the swing;

Fig. 3 is a side elevational view of the swing.

I claim:

The ornamental design for a lawn swing or similar article, as shown.

CHARLES L. MOCK.
